UNITED STATES PATENT OFFICE

MILTON W. POWELL, OF BALTIMORE, MARYLAND

CAP OR STOPPER FOR CONTAINERS AND THE METHOD OF MAKING IT

Application filed September 8, 1927. Serial No. 218,243.

The invention relates to caps or stoppers for milk bottles and the like and has for its object the provision of a cap or stopper including a tab for releasing the cap or stopper from the mouth of the bottle or other container and providing an improved means for reinforcing the face of the tab to prevent it from being pulled out of or off of the cap or stopper.

10 A further object of the invention is the provision of an improved method of making caps or stoppers for containers that are usually cut from sheets of flexible material such as pulpboard by providing the sheets, 15 preliminary to cutting them into disks, with rows of interrupted stitching so positioned that the stitches will be arranged intermediate of the side edges of the disk and at the base of a tab the row of stitching serving to reinforce the base of the tab and to 20 secure it on the disk.

The invention will be described in detail hereinafter and will be found illustrated in the accompanying drawings in which

25 Figure 1 is a top plan view of the cap or stopper made in accordance with my invention,

Figure 2 is a central transverse sectional view through the lifting tab showing the tab in a raised position, and

30 Figure 3 is a fragmental view of the sheets from which the caps or stoppers are made showing the interrupted stitches and the cuts made to form the disks and the tabs.

35 In the drawings similar reference characters are used to designate corresponding parts in all of the views.

The invention consists in forming the caps or stoppers of milk bottles that are usually 40 cut from sheets of pulpboard by cutting the caps or stoppers in the usual manner but prior to the cutting of the caps or stoppers the sheet of pulpboard is passed through a sewing machine to provide the sheet with 45 rows of stitching in intermittent sections. The sewing of the intermittent sections of stitching is performed by a machine arranged to lift the needle, if a single needle machine, or the needles, if a multiple needle machine, from the sheet intermittently, and

to sever the thread each time a needle is lifted so that series of intermittent stitches such as shown in Figure 3 of the drawings is sewed through the board, the stitches being designated 1 in the sheet of pulpboard 55 A. After the sewing operation is completed the sheet is then passed to a cutting machine that cuts it into circular disks 2 by circular incisions 3, and at the same time tabs 4 are provided on the disks preferably by cutting part way through the sheet by cuts indicated at 5, the tabs being so positioned that the stitches 1 on each disk are positioned at the base of the tab thereon and extend a short distance beyond each side of the tab 60 but end short of the outer edge of the disk. By this means a reinforcement or securing means for the tab is accomplished without 65 weakening the cap or stopper.

It will be understood that the sheet A 70 may be printed before the disks are severed and this printing may be done before or after the sewing operation. It will also be understood that sheets may be treated with paraffine or other waterproofing material on 75 one or both sides before the disks are cut therefrom and the sheet may be compressed after the sewing operation and before or after the waterproofing thereof to close the needle holes therein to make the cap or 80 stopper air tight. If preferred the compressing operation and the waterproofing may be deferred until after the disks are formed from the sheet or either or both of the operations may be omitted as may be 85 found expedient.

It is known that disks have been produced having a row of stitching extending across the disk from edge to edge forming a chord of the circle describing the disk cut from a 90 sheet having continuous rows of stitches, but such caps or stoppers have proved to be undesirable because the perforations made by the rows of stitches forms a weakened line on the disk causing it to break often times when closing a bottle therewith, or in any event when the disk is removed from the bottle to decant its contents so that the disk is useless for resealing the bottle as is frequently desired. 95

Furthermore the process of making disks from sheets of material with continuous rows of stitching is undesirable because in cutting the disks from such sheets, in some instances the circular incision is liable to be alongside a needle hole that forms a vent in the edge of the disk that prevents air-tight sealing of the container therewith.

By my method it will be apparent that an air-tight closure can be secured at all times; that the cap is not weakened and when removed from the container to decant a portion of its contents may be replaced to reseal the container. It will also be apparent that caps made by my process can be produced at a less expense than those produced by continuous rows of stitching because of the saving in the stitching material, about sixty per cent thereof, and the waste material after the disks are cut is of greater value because of the absence of threads stitched into it, as the users of such material do not want foreign matter adhering to it.

It will be apparent that instead of cutting the threads when the needle is lifted as above described, the thread may be strung along between the stitches, the unstitched threads being severed at the time the disks are cut from the sheet and the cut particles of thread between the disks may be brushed away to prevent them from getting into the waste.

A great advantage in providing the caps with stitched reinforcements for the tabs is that the stitches do not interfere with capping bottles or other containers as the disks are of uniform thickness and this is not true of caps using wire staples for reinforcing the tabs.

It will be apparent that the stitches may be formed of thread, twine, fine wire, or any other suitable material.

What is claimed is:—

In combination with a bottle stopper comprising a disk formed of fibrous material and having a pulling tab formed from said material and integral with the disk, a reinforcement for said tab consisting of a row of stitches sewed through said disk and arranged at the base of the tab, said row of stitches ending remote from the edges of the disk and providing blank spaces at the ends of the row of stitches, said blank spaces preventing the disk folding on a line defining the row of stitches.

In testimony whereof I affix my signature.

MILTON W. POWELL.
